UNITED STATES PATENT OFFICE.

JOHN M. HANSEN, OF PITTSBURG, PENNSYLVANIA.

METHOD OF REWORKING WORN CAR-AXLES.

940,806.

Specification of Letters Patent. Patented Nov. 23, 1909.

Application filed June 13, 1908. Serial No. 438,420

To all whom it may concern:

Be it known that I, JOHN M. HANSEN, a resident of Pittsburgh, in the county of Allegheny and State of Pennsylvania, have invented a new and useful Improvement in Methods of Reworking Worn Car-Axes; and I do hereby declare the following to be a full, clear, and exact description thereof.

This invention relates to a method of reworking or utilizing worn car axles.

Railroad car axles are subjected to severe wear on the journal portions. The practice is to discard such axles when the journal portions are worn down about $\frac{1}{8}$ of an inch, it being then considered that either the axle is no longer safe or that its reduced diameter entails excessive wear on the journal bearings as well as also being objectionable on account of the loose fit with the bearing.

The life of axles is rather short and as their first cost is large they constitute a heavy item in the maintenance of rolling stock.

The object of this invention is to utilize such worn car axles and re-work the same to at least double the life thereof so as to effect a large saving in the maintenance of rolling stock.

The invention consists in forming and reworking car axles by forming the axle with finished journal and collar portions and after wear, heating and so re-forging the axle as to reduce the length of the end collar and enlarge the journal portion so that after such re-forging it would be at least as large as the original journal portion.

The invention claimed in this application is one of the modifications illustrated and described in my companion application, Serial No. 438,419, wherein the invention is generically claimed.

In the accompanying drawings Figure 1 is a side view showing one end of a worn car axle prior to being subjected to my method; Figs. 2 and 3 are sectional diagrammatic views illustrating the manner of enlarging the diameter of the worn journal portion; and Fig. 4 is a diagrammatic view illustrating the re-turning of the journal portion.

Fig. 1 shows a portion of a worn car axle having the main body or central portion 1, the portion 2 upon which the wheel is secured, the journal 3 and the end collar 4. The dotted lines 5 show the original diameter of the journal portion, so indicating the manner in which the same has been worn.

This axle may be similar to the standard axles in all particulars except that an excess of metal is provided in its end portion, that is, in the end collar 4. The dotted line 6 indicates the usual length of a standard car axle and all of the metal beyond said dotted line is excess.

When this axle has become worn it is subjected to a suitable forging operation to again enlarge its journal to or beyond its original diameter so that the latter can again be re-turned and used the same as a new axle. Fig. 2 illustrates one manner of effecting this result. The end of the axle is heated and then subjected to an up-setting operation, such as by means of the up-setting dies 7 carried by a suitable plunger 8 which may be operated by a hydraulic cylinder or other suitable means. The axle is held and grasped by means, such as dies 9 which are made to grip the axle inside the journal portion, so holding the axle against the thrust of the upsetting die. Preferably also these dies 9 are extended to inclose the journal portion but not tightly, leaving a space therebetween. Fig. 2 shows a space 10 and shows the parts in position before the upsetting operation, while Fig. 3 shows the same parts after the upsetting operation 85 in which the metal has been forced inwardly by the upsetting die, so reducing the length of the end collar and increasing the diameter of the journal portion so that after such re-forging the journal portion will be at least 90 as large as the original journal portion. It will thus be seen that by making the end collar of the original axle of greater length than required, sufficient metal is provided for such enlarging of the journal portion by 95 the upsetting operation. The metal is prevented from flowing inwardly beyond the journal portion on account of the gripping dies 9 and consequently when upset must flow radially and increase the diameter of 100 the journal portion. The metal will fill out into the parts of the dies inclosing the journal portion and in this manner the journal portion will be enlarged and re-shaped.

The excess of metal in the end collar 4 in all cases will be made sufficient so that when the journal portion is upset the axle will have a collar of the usual size and a journal as large as in the original forged axle so that said journal can again be turned down 105 to the same size as the journals of new axles. This re-turning is illustrated in Fig. 4.

According to this method the axle may be made capable of being re-forged a plurality of times by providing a sufficient quantity of excess metal in the end collar, and in the successive re-forgings said end collar will be reduced in length at each re-forging. The re-forged axle has a journal portion of the same size and consequently the same strength as a new axle.

10 It will be readily seen that according to this method the life of the axle can be doubled and even trebled by rather simple operations and at comparatively small cost, much less than the cost of a new axle. This 15 will materially reduce the cost of maintenance of the rolling stock.

What I claim is:

The method of forming and re-working car axles, consisting in forming the axle with finished journal and collar portions, 20 and after wear heating and re-forging the same so as to reduce the length of the end collar and so enlarge the journal portion that after re-forging it will be at least as large as the original journal portion.

In testimony whereof, I the said JOHN M. HANSEN have hereunto set my hand.

JOHN M. HANSEN.
